[57] CLAIM

The ornamental design for a shoe-shaped tote bag, as shown and described.

DESCRIPTION

FIG. 1 is a perspective view of shoe-shaped tote bag showing my new design;

FIG. 2 is a back elevational view thereof showing the location of a two-zippered back pocket;

FIG. 3 is a front elevational view thereof showing the location of a zippered front pocket;

FIG. 4 is a side elevational view showing the location of a see-through identification pocket opposite side elevational view being the same; and,

FIG. 5 is a bottom plan thereof.

FIG. 1

FIG. 2

FIG. 3

FIG. 4

FIG. 5
